UNITED STATES PATENT OFFICE.

BUSHROD C. WASHINGTON AND STUART K. JOICE, OF WASHINGTON, DISTRICT OF COLUMBIA.

FAN.

1,424,961.

Specification of Letters Patent.

Patented Aug. 8, 1922.

Application filed September 23, 1919. Serial No. 325,690.

To all whom it may concern:

Be it known that BUSHROD C. WASHINGTON and STUART K. JOICE, citizens of the United States, residing at Washington, in the District of Columbia, have invented certain new and useful Improvements in Fans, of which the following is a specification, reference being had therein to the accompanying drawing.

- 10 The invention relates to fans and has for its object to provide a hand operated rotary fan and to provide a reciprocating double rack operating gears in mesh with gears which operate the fan shaft and ratchet and pawl mechanisms whereby as the rack is reciprocated one of the fan operating gears will drive the fan alternately according to the direction of movement of the double rack.
- 20 A further object is to provide a rotary hand operated fan so constructed that the fan will be rotated on the downward and upward movement of simultaneously moved reciprocating racks, said fan on both movements being rotated in the same direction.
- 25 Also to provide ratchet and dog mechanisms by means of which the reciprocating racks may be stopped at any point without retarding the rotation of the fan.
- 30 A further object is to provide spring means whereby the reciprocating double rack on its outward stroke will be assisted in its movement, thereby relieving the strain on the finger of the operator during the reciprocation of the double rack.

35 A further object is to provide a rotary fan particularly adapted for dances, use in moving picture theaters and the like, said rotary fan being hand operated and reduced to its minimum in size so that the same may be easily carried in a purse, pocket or if so desired suspended from a chain from the wrist. Also to so construct the driving mechanism for the rotary fan so that it will be double acting, that is operate the same through gears and racks in such a manner that as the racks are reciprocated the fan will be rotated on both strokes of said racks.

With the above and other objects in view 50 the invention resides in the combination and arrangement of parts as hereinafter set forth, shown in the drawings, described and claimed, it being understood that changes in the precise embodiment of the invention

may be made within the scope of what is claimed without departing from the spirit of the invention.

In the drawings:

Figure 1 is a view showing the position in which the fan is preferably held for operation.

Figure 2 is a rear view of the fan.

Figure 3 is a plan view of the fan with parts broken away to illustrate the driving mechanism.

Figure 4 is a rear view of the fan with parts broken away to show the driving mechanism.

Figure 5 is a sectional view taken on line 5-5 of Figure 2.

Figure 6 is a detail view of the under sides of the driving gears and ratchets and dogs through the medium of which the driving gears are revolved alternately upon the reciprocation of the racks.

Figure 7 is a sectional view taken on line 7-7 of Figure 3.

Referring to the drawings, the numeral 1 designates a base plate upon which the fan operating mechanism is carried and is adapted to be supported. Base plate 1 has at one side thereof a finger engaging member 2, in which member the finger of the operator is adapted to enter, however it is to be understood that this member may be of any depth and wide enough to receive one or more fingers, so as to stabilize the fan as a whole during a fanning operation. However for purpose of illustration, curved lugs 3 are shown extending outwardly and inwardly from the sides of the member 2 and between said lugs and the body of the fan, the fingers are adapted to pass while one or more fingers are disposed within the member 2.

95 A double reciprocating rack 4 is slidably mounted on one face of the plate 1 and is held in position by a guide plate 5 which is disposed on a spacing block 6 and through which guide plate spacing block and through 100 plate 1, screws 7 pass. Spacing block 6 is disposed within the elongated aperture 8 in the reciprocating double rack. Thus it will be seen that as the double rack bar 4 is reciprocated that the racks 9 and 10 will be 105 guided in their movement and the double rack bar 4 as a whole prevented from displacement. Guide plate 5 has rotatably

mounted in a bearing 11 thereof a fan shaft 12, which fan shaft has pivotally secured to the outer end thereof a series of fan blades 13 which may be of any construction but are 5 preferably foldable and of a type wherein as the fan shaft 12 is rotated the blades will automatically open. Fan shaft 12 also has a bearing 14 in a bridge plate 15, which bridge plate is supported on posts 16 carried 10 by the body plate 1 thereby holding the fan shaft in position. Keyed or otherwise secured to the fan shaft 12 is a gear 17, which gear is adapted to be rotated in the same direction by means of gears 18, which 15 mesh with the gear 17 and are disposed on opposite sides of the same. Gears 18 are loosely mounted on shafts 19, supported in bearings 20 and 21 in the bridge plate 15 and the base plate 1. The upper faces of 20 the gears 18 are provided with annular depressions 22 in which depressions spacing washers 23 are disposed, said spacing washers having a tight fit on the shafts 19 and are provided to prevent the frictional binding 25 of the upper faces of the gears 18 against the under face of the bridge plate 15. Gears 18 are held in position by pinions 24 which are loosely mounted on the shafts 19, the upper ends of said pinions being provided 30 with integral ratchets 25 by means of which ratchets and spring actuated pawls 26, gears 18 and pinions 24 will be locked to rotate with each other alternately with the reciprocation of the racks 9 and 10 which are 35 carried by the reciprocating rack bar 4. Secured as at 28 to the end of the rack bar 4 and to the base plate 1 as at 29 is a coil spring 30, which coil spring is adapted to assist the return of the rack bar 4 to its outward position, however it is to be understood that this spring if so desired may be 40 eliminated and the rack bar 4 moved to its outward position by means of the finger of the operator, preferably the thumb which 45 is disposed within the socket 31 at the outer end of the rack bar.

A casing 32 is provided which casing is adapted to enclose the mechanism of the fan. Casing 32 is preferably formed in two 50 sections, 33 and 34 telescopically engaging each other and are provided with diametrically arranged and registering apertures 35 for the reception of the shank of the member 2 and the reciprocating rack bar 4. The 55 rear portion of the casing 32 has detachably secured thereto a dish shaped receptacle 36, in which dish shaped receptacle a powder puff 37 is disposed. In the bottom of the dish shaped receptacle 36 a mirror 38 is secured in any suitable manner. It will be 60 seen that when it is desired to use a powder puff and mirror it will only be necessary to remove the dish shaped member 36 from the rear of the casing 2 and that said dish shaped member, may be quickly removed 65

and replaced. Dish shaped member 36 may be threaded or frictionally held on the casing 32.

Dogs 26 are pivoted on the gears 18 as at 39 and are normally held in engagement 70 with the teeth of the ratchet 25 by means of springs 40, which springs may be secured to the gears 18 in any suitable manner but preferably soldered as at 41.

It will be seen by referring to Figures 4 75 and 5 that as the rack bar 4 is forced inwardly that the rack 10 will cause the pinion 24 to revolve in the direction of the arrow *a*, which will cause the dog 26 on the gear 18 to engage in the teeth of the ratchet 80 25, thereby locking the gear 18 and pinion together, and as the gear 18 meshes with the gear 17 the fan shaft will be revolved in the direction of the arrow *b*, the gear 18 at the other side of the rack bar 4 will run 85 idle for the reason that its ratchet and dog would cam by each other and even if they do not cam by each other, the gear 18 being loosely mounted would revolve on its shaft 19 independently. When the rack bar 4 re- 90 turns to its outward position it will be seen that its engaging pinion 24 will go in the opposite direction thereby throwing its ratchet into engagement with the nose of the dog 26 so that the gear 18 will be caused 95 to rotate in the direction of the arrow *c* thereby continuing the rotation of the fan shaft 12 in the direction of the arrow *b*.

From the above it will be seen that a hand operated fan is provided wherein a continuous 100 rotation of the fan is accomplished on both strokes of the reciprocating rack bar, and one wherein a full stroke is not necessary as the reciprocation may be stopped at any point or may be of any length. It will 105 also be seen that by means of the finger engaging members the possibility of the operator's fingers extending through to such a point where they will be engaged by the rotating fan blades is obviated.

The invention having been set forth what is new and useful is:—

1. The combination with a stationary casing having a fan actuating motor therein, said motor being actuated by a reciprocating 115 rack moved inwardly manually and outwardly under the impulse of a spring, said rack being provided with a finger receiving socket having its side adjacent the casing inclined inwardly towards the casing thereby providing a finger engaging surface which will prevent slippage of the finger and a finger engaging socket carried by the casing opposite the rack socket and having its inner side at substantially a right angle 120 to the casing for preventing slipping of the finger, said socket forming means for preventing the fingers from coming into the path of the fan during a fan operation.

2. The combination with a finger operated 130

fan disposed within a casing and operated by placing the thumb and forefinger in oppositely disposed members having sockets therein, one of said members being carried by a rack bar, of a casing for said fan, said casing being cylindrical shaped and through the opposite walls of which the rack bar and one of the finger engaging members extend, a removable cover telescopically engaging one side of the casing, said cover being dis-

posed adjacent the open sides of the finger engaging members thereby being positioned where during a fan revolving operation the cover may be held from displacement by the hand.

15

In testimony whereof we hereunto affix our signatures.

BUSHROD C. WASHINGTON.

STUART K. JOICE.
